SHOE MACHINE

Albert F. Bancroft, West Newton, Mass., assignor
to Bancroft-Walker Company, Waltham, Mass.,
a corporation of Massachusetts

Application December 29, 1936, Serial No. 118,075

8 Claims. (Cl. 12—49.1)

This invention pertains to the manufacture of footwear and relates more particularly to apparatus useful in covering shoe heels. In the manufacture of shoes, particularly those having the so-called Cuban type of heel, it is customary to finish the breast surface of the heel by applying a piece of thin sheet material, for example leather, which is adhesively secured to the heel, which may be of wood, fiberboard, leather or other material customarily used and appropriate for the purpose. Usually the lateral surface of the heel is first finished, as by covering it with thin sheet material, this finishing material either being carried around and lapped over to cover the breast surface in whole or in part, or being trimmed off flush with the forward corners of the heel, the breast surface then being covered by a separate piece of sheet material whose edges abut or overlap and substantially conceal and cover the edges of the outer or lateral covering of the heel. In the latter case in particular, any failure of the breast covering material to adhere permanently to the breast surface of the heel results, during wear, in a separation or partial separation of the breast-covering material from the lateral covering at the corners of the heel, producing an untidy, frayed or ragged appearance greatly detracting from the intended neatness and daintiness of footwear of the finer grades. This separation of the breast covering is apparently not due to any inadequacy in holding power of the adhesives employed for this purpose but rather to the failure of the operator to press the covering so firmly against the breast of the heel proper as to insure uniform adhesion, or to hold the covering material in close association with the surface of the breast until the adhesive has completely set.

The principal object of the present invention is to provide means whereby the breast-covering material may be adequately pressed against the breast surface and firmly held until the adhesive employed has had time to set and thus to secure the covering permanently to the breast surface at the edges as well as at intermediate points.

While the breast surface of the heel is customarily concavely curved transversely, this curvature varies with shoes of different makes and styles, and in fact this breast surface may in some cases be substantially flat. It is a further object of the invention to provide heel covering apparatus capable of use with heel breasts of any of the usual configurations.

Other objects are to provide apparatus of simple, inexpensive and durable type capable of use by operators having relatively little skill;

which does not interfere or interrupt the usual course of procedure in the factory; and which makes it possible to speed up the operation of heel breast covering as well as to improve the product.

Other objects and advantages of the invention will be made manifest in the following more detailed description and by reference to the accompanying drawings illustrating certain desirable embodiments of the invention by way of example, and wherein

Fig. 1 is a fragmentary plan view of a preferred form of apparatus embodying the present invention;

Fig. 2 is a fragmentary vertical section substantially on the line 2—2 of Fig. 1;

Fig. 3 is a fragmentary front elevation of the apparatus of Fig. 1;

Fig. 4 is a transverse horizontal section of a shoe heel of the type known as a "Cuban" heel, showing the covering material for the lateral and breast surfaces;

Fig. 5 is a diagrammatic plan view, to small scale, illustrative of another embodiment of the invention;

Fig. 6 is a vertical section substantially on the line 6—6 of Fig. 5; and

Fig. 7 is a fragmentary vertical section, substantially like Fig. 2, but illustrating a further modification.

Referring to Fig. 4, the heel H comprises the heel proper or core 1 which may be of wood or any other of the usual materials employed in heel making. The lateral surface 2 of this core member is provided with a finish, for example, a coating 3 consisting of sheet material such, for example, as leather, cloth, artificial leather or the like, suitably secured to the core by means of adhesive and, as shown in Fig. 4, having its forward edges 4 and 5 trimmed off substantially flush with the breast surface 6 of the core member.

This breast surface 6 is also provided with a finish, such as a layer 7 of leather, artificial leather, cloth or the like which is secured to the breast surface of the core by means of adhesive 8—the lateral edges of this breast covering 7 preferably overlapping and concealing the forward ends of the covering 3. Ordinarily, the covering 3 for the lateral surface is first applied to the core, and after the adhesive has thoroughly set the breast covering 7 is applied. This breast covering is usually applied by hand, but since the adhesive, even though of quick setting type, does not always set instantaneously, and since the smoothing action and pressure of the operator's fingers, or

of a manually operated pad provided for the purpose, is all that is available for causing the covering to lie snugly against the breast surface and to insure uniformity of contact and adhesion, 5 it frequently happens, either through failure initially to lay the covering smoothly into intimate contact with the breast surface, or because the covering is not held under pressure throughout its entire area until the cement has set, that 10 there may be unattached portions forming blisters, bubbles, or areas which are not thoroughly and permanently attached, so that during wear the breast covering separates more or less from the breast surface of the core. When this separation 15 takes place, in particular along the forward corners of the heel, it results as previously pointed out in a ragged and unkept appearance greatly detracting from the desired daintiness of the shoe.

20 Referring to Figs. 1 to 3 there is illustrated a very simple form of apparatus useful in the breast covering operation, and the use of which substantially insures a proper and permanent adhesion of the breast covering to the breast sur- 25 face of the core.

B represents a bench upon which is mounted a heel rest or abutment 9. Preferably this heel rest is of sufficient length so that a plurality of heels may be mounted upon it in end-to-end relation at the same time. The upper surface 10 of this elongate heel rest 9 is preferably convex upwardly with a transverse curvature more or less conforming to that of the transverse curvature of the heels to be covered. If desired the 30 support 9 may be removably mounted on the bench B and a plurality of such supports, having differently curved surfaces 10 may be provided for use with heels of widely different breast curvature. However, it is preferred to provide the 35 rest 9 with a pad 11 covering the surface 10, said pad being of resiliently yieldable material, such for example, as rubber, felt, sponge rubber, or a fluid inflated flexible bag, such pad being adapted to conform itself under pressure to the breast 40 surface of the heel resting thereupon.

A horizontal shaft 12 is arranged to extend substantially parallel to the length of the rest 9, being preferably disposed somewhat above the level of the upper surface of the pad 11. This 45 shaft 12 is conveniently mounted in brackets 13 carried by the base B, and on this shaft is mounted a series of lever arms 14, 14^a, 14^b, 14^c, etc. corresponding in number to the number of heels which may conveniently be mounted at the same 50 time on the heel rest 9. As illustrated, these lever arms 14, 14^a, etc. are designed to swing in parallel, substantially vertical planes perpendicular to the length of the rest 9. These lever arms 55 may be held in proper spaced position on the shaft 12 by means of collars C and, for convenience in operating them, each lever may be furnished, if desired, with a handle 15 at its extreme forward end. In the simple embodiment illustrated in Figs. 1, 2 and 3 these lever arms 14, 14^a, etc. are 60 made of substantial weight, for example of more or less cylindrical iron bars, so that gravity alone furnishes the desired heel pressing force.

Adjacent to the forward end of each of the 65 levers 14, 14^a, etc. there is preferably arranged a heel engagement element 16, for example a pad having a resilient heel-contacting surface 17 (Fig. 3) designed to engage the rear surface of a heel positioned with its breast surface on the 70 rest 9. Preferably each pad 17 is so mounted

upon its lever arm as to permit the pad to rock about the axis of the arm, thereby to accommodate itself to the contour of the surface of the heel with which it contacts. Thus as shown in Fig. 2, the forward part 18 of the lever arm 14, 5 for example, may be of reduced diameter so as to form a pivotal support for the pad 16.

If desired, each bracket 13 may be furnished with a rearwardly and upwardly extending arm 19 which supports an elongate stop bar 20 provided, if desired, with a cushioning pad on its upper face, such stop bar extending across the planes of movement of the several lever arms and being adapted to hold any of the lever arms in a rearward inoperative position when desired. 15

In using this apparatus, it being assumed that a heel H has been furnished with its lateral covering 3 and that the breast covering 1 has just been laid in place by hand,—the adhesive still being somewhat fluid, the right hand lever arm 20 14, for example, may be raised and the heel H disposed with its covered breast surface resting upon the pad 11 immediately beneath the pad 16 of the lever 14. The lever arm is now lowered until the pad 16 rests upon the rear surface of 25 the heel H. As above noted, the weight of the arm 14 may be quite substantial, for example the arm may be of ten pounds or more in weight and thus when the pad 16 is permitted to rest on the heel the breast surface of the latter is pressed 30 very firmly against the yielding covering 11. Since this covering conforms itself to the breast surface of the heel, the thin, flexible heel covering is pressed with substantial uniformity against the breast surface of the heel core and with very 35 considerable pressure, thus insuring uniformity of contact and smoothness of the heel covering.

The lever 14 may rest upon the heel, while the next lever 14^a of the series is raised and a heel H^a is disposed beneath the pad of the latter lever. This operation may be continued, heels H^b and H^c being successively disposed on the rest 9 and beneath the pads of the lever arms 14^b, 14^c, etc. until the available space on the rest 9 has been fully taken up. The operator now returns to the first lever 14, lifts it and removes the heel H and places a fresh heel with its breast covering beneath the lever H and so continues in succession, removing heels from beneath the several levers and replacing them with new ones. It is contemplated that the number of levers and the length of the rest 9 may be such that by the time the operator returns to remove the heel from beneath the first lever, the adhesive will have firmly set. 55

In Figs. 5 and 6 a modification is illustrated designed more particularly for the convenience of the operator. In this arrangement a series of heel rests 9^a is disposed peripherally of a horizontal, rotatable table T mounted for free rotation on a support carried by the bench B. With each of the heel rests 9^a there is associated a lever arm 14^x, 14^y, 14^z, etc. each arm being pivotally mounted on a bracket 13^a carried by the table T. Each of the lever arms 14^x, etc. may be provided with a handle 15 for lifting it and with a heel-engaging pad 16^a for engagement with a heel H resting upon the corresponding rest 9^a. In this instance, instead of making the lever arm 14^x, etc. of sufficient weight so that gravity supplies 70 all of the desired pressure, each arm may be furnished with a spring 21 so connecting the arm to the table that the arm is urged downwardly with the desired pressure. Obviously, if desired, means may be furnished whereby the tension of 75

the springs 21 may be varied in accordance with the work to be operated upon.

In Fig. 7 a further modification is illustrated wherein the bench B carries an elongate heel rest 9 provided with a heel supporting pad 11 such as above described and having a shaft 12^m, carried by a bracket 13^m, which supports a series of lever arms 14^m each having a pad 16^m at its free end designed to rest upon the rear surface of a heel H and thus to press the breast surface of the heel against the pad 11 of the heel rest 9.

In this instance the bench B is furnished with an opening B' (or a series of openings) and through this opening there extends a link device, 15 corresponding to each of the lever arms 14^m, each 20 link device being pivotally secured at its upper end to the corresponding lever arm. These link devices are preferably of extensible character, each comprising an upper portion 23 and a lower portion 24. The upper portion is furnished with 25 an apertured flange 25 at its lower end through which the upper part of the member 24 projects, such upper part being furnished with a head 26 at its upper end which slides in a slot 26^a in the part 23, the upper end wall of the slot constituting an abutment to limit upward movement of the member 24. A spring 27, interposed on the flange 25 and the head 26 permits relative yielding 30 of the two link members 23 and 24 in a longitudinal direction. The link member 24 is pivotally connected at its lower end to a long treadle lever 28 pivotally supported at 29 to a bracket 30 projecting downwardly from the bench B, the treadle lever being furnished with a treadle 31 35 at its forward end at a convenient point for engagement by the foot of the operator. A spring 32 tends to raise the lever 28 and, through the link connection, to lift the corresponding lever arm 14^m to the broken line position of Fig. 7.

40 Preferably the treadle lever 28 is furnished with a lateral flange 33 which may engage detent teeth 34 on a sector plate 35 carried by the bench B.

In the operation of this device and assuming that the treadle lever 28 is in the upper broken line position and that the lever arm 14^m is correspondingly raised, the operator places a heel H on the pad 11 and then depresses the treadle 31, thereby swinging the arm 14^m downwardly so as to bring the pad 16^m into contact with the rear surface of the heel. The yielding of the link device, as provided for by the spring 26, permits the operator to apply very substantial resilient pressure to the heel and at the same time to engage the flange 33 beneath one of the detent teeth 34, this engagement being accomplished by a slight lateral movement of the treadle lever 28. The heel may now be left under pressure,—the treadle being held locked, until the operator has in a similar way lowered the other pressure applying arms 20^m. The operator then returns to the first lever 14^m and by depressing the treadle 21 and swinging the arm 28 laterally to a slight extent, the treadle is released from the detent and allowed to rise, thus permitting the operator 65 to remove the heel.

While certain embodiments of the invention have been illustrated, it is to be understood that the invention is not necessarily limited to these particular arrangements, but is to be regarded as 70 inclusive of any modification and/or equivalent constructions falling within the scope of the appended claims.

I claim:

75 1. Apparatus of the class described comprising a support for a shoe heel, said support having

ing a heel-engaging surface approximating the shape of the breast of the heel, and a movable pressure-applying member having a heel-engaging pad engageable with the rear surface of a heel disposed with its breast in contact with the heel-engaging surface of the support, said pad being movably united to said pressure-applying member thereby to permit it to accommodate itself to the contour of the heel.

2. Apparatus of the class described comprising 10 a rest for a shoe heel, said rest having a heel-engaging surface approximating the shape of the breast of the heel, a pressure-applying lever pivotally supported to swing in a substantially vertical plane about an axis so located with reference 15 to the heel rest that the free end portion of the lever may contact and apply pressure to the rear surface of a heel disposed with its breast in contact with the heel-engaging surface of the rest.

20 3. Apparatus of the class described comprising a rest for a shoe heel, said rest having a heel-engaging surface approximating the shape of the breast of the heel, a pressure-applying lever pivotally supported to swing about an axis 25 so located with reference to the heel rest that the free end portion of the lever may contact the rear surface of a heel disposed with its breast in contact with the heel-engaging surface of the rest, said lever being so disposed and of 30 such weight as when in contact with the heel to exert substantial pressure thereagainst.

4. Apparatus of the class described comprising 35 a heel rest having a heel-supporting surface of sufficient length to accommodate a plurality of shoe heels, said supporting surface being transversely contoured to approximately the transverse contour of the breast surface of a shoe heel, and a plurality of independent pressure-applying levers pivotally supported to swing in substantially parallel planes, each lever being provided with a heel-engaging element operative to contact with and apply pressure to a shoe heel disposed with its breast in contact with the heel-supporting surface of the rest thereby to force 40 the heel breast against the support.

5. Apparatus of the class described comprising 45 a heel rest having a heel-supporting surface of sufficient length to accommodate a plurality of shoe heels, said supporting surface having a 50 transverse contour approximating the transverse contour of the breast surface of a shoe heel but being resiliently yieldable more readily to accommodate itself to the contour of said surface of a shoe heel, and a plurality of independent levers, each lever being pivotally supported to swing in a vertical plane intersecting the supporting surface, each lever having a heel-engaging element and a handle portion whereby it may be lifted, each lever being of such weight as, when resting upon a heel disposed with its breast 55 in contact with the supporting surface of the rest, to exert substantial downward pressure against the heel.

6. Apparatus of the class described comprising 60 a heel rest having a heel-supporting surface of sufficient length to accommodate a plurality of shoe heels, said supporting surface having an approximate transverse contour to conform with the transverse shape of the breast of a shoe heel, and a plurality of movable pressure applying 70 members each having a heel-engaging pad engageable with the rear surface of a heel disposed with its breast in contact with the heel supporting surface of the heel rest each of said pads being movably united to the corresponding 75

pressure applying member thereby to permit it to accommodate itself to the contour of the corresponding heel.

7. Apparatus of the class described comprising a heel rest having a heel-supporting surface of sufficient extent to accommodate a plurality of shoe heels, said supporting surface having an approximate transverse contour to conform with the transverse shape of the breast of a shoe heel, 5 a plurality of pressure applying levers each pivotally supported to swing about an axis so located with reference to the heel rest that the free end portion of each lever may contact the rear surface of a heel disposed with its breast in contact with the heel-engaging surface of the rest. 10 15

8. Apparatus of the class described comprising a heel rest having a heel-supporting surface of sufficient extent to accommodate a plurality of shoe heels, said supporting surface having an approximate transverse contour to conform with the transverse shape of the breast of a shoe heel, 5 a plurality of pressure applying levers each pivotally supported to swing about an axis so located with reference to the heel rest that the free end portion of the lever may contact the rear surface of a heel disposed with its breast in contact with the heel-engaging surface of the rest, each of said levers being so disposed and of such weight as when thus in contact with a heel to exert substantial pressure thereagainst. 10 15

ALBERT F. BANCROFT.
